FREEZING POINT DETERMINATION INSTRUMENT

Rolf E. Darbo, Madison, Wis.

Application December 31, 1954, Serial No. 33,775

Term of patent 14 years

(Cl. D52—7)

Fig. 1 is a front view of a freezing point determination instrument embodying my new design;

Fig. 2 is a side view thereof looking at the instrument from the left hand side;

Fig. 3 is another side view looking at the instrument from the right hand side;

Fig. 4 is a top plan view of the instrument shown in Fig. 1;

Fig. 5 is a cross-section taken on the line 5—5 of Fig. 1; and

Fig. 6 is a bottom view thereof.

The dominant features of the design reside in the solid line portions.

I claim:

The ornamental design for a freezing point determination instrument, as shown and described.
